Patented May 4, 1965

201,031

SEAT BELT HOUSING OR THE LIKE

Maurice F. Baldwin, Birmingham, Mich., assignor to
Industro-Motive Corporation, Troy, Mich., a corpora-
tion of Michigan

Filed Jan. 17, 1964, Ser. No. 78,238

Term of patent 3½ years

(Cl. D41—1)

Fig. 1

Fig. 2

Fig. 3

Fig. 4

FIGURE 1 is a side elevational view of a seat belt housing or the like showing my new design;

FIGURE 2 is a bottom plan view thereof;

FIGURE 3 is an end elevational view as seen from the left of FIGURE 1; and

FIGURE 4 is a perspective view taken from the right of FIGURE 1.

I claim:

The ornamental design for a seat belt housing or the like, substantially as shown.
